AUTOMATIC LACED INNER BELT FOR
FOUNDATION GARMENTS

Frank A. Cohen, New York, N. Y.

Application April 2, 1940, Serial No. 327,432

1 Claim. (Cl. 2-27)

This invention relates to new and useful improvements in an automatic laced inner belt for foundation garments.

The invention proposes a foundation garment having a body with a vertically extending opening in the abdominal region, and elastic belt sections having their inner ends adjacent the edges of said opening and their outer ends attached to the material of the body. Moreover, the invention contemplates a lace simultaneously securing the edges of the opening and the inner ends of the belt sections together. With this arrangement it is possible to manipulate the tension of the lace to control the opening and the elastic belt sections simultaneously.

Still further the invention contemplates to so construct the belt sections and the opening in the garment body that the construction may be placed at various areas upon a foundation garment. The construction may be at the front of the garment or at the rear.

Still further the invention contemplates so arranging the construction of the abdominal opening in the belt section that it may be applied to various types of foundation garments. It is proposed that the construction be applicable to girdles, to foundation garments having connected brassières, and to other types of foundation garments.

Still further the invention proposes an arrangement whereby the belt sections may be drawn in, or let out to vary the space relationship of the ends of the belt sections and the edges of the opening.

Still further the invention proposes to use the said lacing construction either at the front or back or both at the front and back of all type of foundation and like garments.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:

Fig. 1 is a front elevational view of a foundation garment equipped with a connected brassière and constructed in accordance with this invention.

Fig. 2 is a horizontal sectional view taken on the line 2-2 of Fig. 1.

Fig. 3 is a fragmentary enlarged vertical sectional view taken on the line 3-3 of Fig. 1.

Fig. 4 is an elevational view of a foundation

garment similar to the one illustrated in Fig. 1 but constructed in accordance with a modification of this invention.

Fig. 5 is a fragmentary enlarged perspective view of one of the belt sections used in the garment shown in Fig. 4.

Fig. 6 is a perspective view of another type of foundation garment constructed in accordance with this invention.

10. Fig. 7 is a horizontal sectional view taken on the line 7-7 of Fig. 6.

Fig. 8 is a vertical sectional view taken on the line 8-8 of Fig. 7.

The foundation garment, in accordance with 15. this invention includes a foundation garment body 10 which may be made of any suitable fabric or material and have a vertically extending opening 11 in the abdomen region. Elastic belt sections 12 have their inner ends adjacent the edges of the opening 11 and have their outer ends attached to the body 10 with lines of stitches 13. The edges of the opening 11 are finished with reinforcement straps 14 attached thereon. These reinforcement straps 14 support a plurality of eyelets 15 arranged along the edges thereof. The adjacent edges of the belt sections 12 are also reinforced with reinforcement strips 16. These reinforcement strips 16 are provided with eyelets 17. The eyelets 15 and 17 20 are arranged to be adjacent each other so that a lace, for example the lace 18 illustrated in Figs. 2 and 6, may be laced through the eyelets 15 and 17. Then the opening 11 and the belt sections 12 may be simultaneously closed by drawing upon the lace 18 and tying the lace 18.

The foundation garment body, as illustrated in Fig. 1, is of the corsette type. At the top it is provided with a brassière portion 19. This brassière portion comprises merely the front section of a brassière (see Fig. 2) which is attached at its ends by the stitches 13 to the material of the belt 12 and the garment body 10. The brassière 19 is provided with the usual shoulder straps 20. Along the bottom edge the garment body 10 is provided with the usual garter supports 21. An inspection of Figs. 1 and 3 will disclose that the upper portions of the belt sections 12 extend upwards of the bottom edge 19' of the brassière 19. Thus the belt sections assist 25 in holding the brassière down in proper position. Fig. 2 illustrates the lace 18 engaged through the eyelets 15 and 17. The lace 18 has not been shown in Fig. 1 as it is believed that because of the small scale of this figure it would confuse 30 the same.

In Figs. 4 and 5 a modified form of the invention has been disclosed which distinguishes from the prior form in the fact that the foundation garment body 10' is provided with a rear opening 11' in the abdominal region. Elastic belt sections 12' have their inner ends adjacent the edges of the opening 11' and have their outer ends attached to the material of the body 10' by stitches 13'. The edges of the opening 11' are reinforced with strips 14'. These straps are provided with eyelets 15'. The inner edge portions of the belt sections 12' are reinforced with strips 16'. These strips 16' are provided with eyelets 17'. A lace, such as the lace 18, is intended to be laced through the eyelets 15' and 17' so that the belt sections and the opening may be simultaneously closed.

The garment body 10' is provided with a brassière section 19 having shoulder straps 20. Garter supports 21 are arranged at the bottom of the garment body 10. Each belt section 12' is provided with a means for drawing in or letting out the inner edges thereof to vary the space relationship of the ends of the belt sections 12' in relation to the edges of the opening 11'. Specifically, this means includes a vertically extending fold 24 formed in the material of each belt section 12'. These folds 24 have eyelets 25 in each of the layers thereof arranged in vertical rows. A lace 26 is laced through the eyelets 25. The lace 26 may be drawn tight to hold the fold 24 completely closed. Then the belt section is of its minimum size and its inner edge is disposed a maximum distance from the edge of the opening 11'.

When desired the lace 26 may be loosened so that the fold 24 opens to any extent desired. This extends the length of the belt section. In this manner the belt section may be extended to various points so that the eyelets 15 and 17 are in various spaced relationships to each other. A lace is laced through the eyelets 15 and 17 as described before. With this arrangement it is possible to vary the tension of the belt sections 12'. It is intended that these belt sections 12' be of elastic material. Similarly, the material of the foundation garment 10' may also be elastic.

In Figs. 6 and 7 another embodiment of the

invention has been disclosed. In accordance with this form of the invention the foundation garment includes a foundation garment body 10'' of the girdle type. The front, or the rear of this body 10'' is formed with an opening 11 at the abdominal region. Elastic belt sections 12 have their inner ends adjacent the edges of the opening 11 and have their outer ends attached to the body 10'' by stitches 13. The edges of the opening 11 are reinforced with strips 14 which have eyelets 15 mounted along their edges. The inner edges of the belt sections 12 are reinforced with strips 16 which have eyelets 17 mounted along their inner edges. A lace 18 is laced through the eyelets 15 and 17. Then this lace 18 is pulled tight and the opening 11 is pulled closed and simultaneously the sections of the belt are drawn together. The garment body 10'' has the usual garter supports 21 on its bottom edge.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

An automatic laced inner belt for foundation garments, comprising in combination a foundation garment body having a vertically extending opening in the abdomen region, elastic belt sections having their inner ends adjacent the edges of said opening and their outer ends attached on said body, eyelets along the free edges of said belt sections and opening for a lace by which the belt sections and opening may be simultaneously drawn together and closed respectively, and means for adjusting the length of said belt sections to vary the space relationship of the ends of the belt sections and the edges of said opening, said means comprising a vertically extending fold in each belt section, and means for holding the fold formed in the desired adjusted position.

FRANK A. COHEN.
